UNITED STATES PATENT OFFICE

MICHAEL SCHWARZ AND FRED J. GOETZ, OF ST. LOUIS, MISSOURI, ASSIGNEES TO
CRUNDEN-MARTIN MANUFACTURING COMPANY, OF ST. LOUIS, MISSOURI, A COR-
PORATION OF MISSOURI

RECEPTACLE

Application filed October 25, 1929. Serial No. 402,436.

This invention relates to receptacles and more particularly to cover fasteners for garbage receptacles. It has for its principal object to devise a simple and efficient cover fastener which serves as a handle for placing the cover on and removing it from the receptacle. Other objects are ease of operation, economy and compactness of design and fewness of parts. The invention consists in the cover fastener and in the construction, combinations and arrangements of parts hereinafter described and claimed.

In accompanying drawing which forms part of this specification and wherein like symbols refer to like parts wherever they occur,

Fig. 1 is a plan view of a receptacle cover provided with a fastener embodying our invention, the fastener being shown in locking position.

Fig. 2 is a vertical section through the receptacle and cover therefor, the section being taken on the line 2—2 in Fig. 1,

Fig. 3 is a view similar to Fig. 2, with the cover fastener shown in unlocked position,

Fig. 4 is a fragmentary side elevation of the receptacle adjacent to the outer end of the fastener,

Fig. 5 is a vertical section on the line 5—5 in Fig. 1,

Fig. 6 is a vertical section through the cover on the line 6—6 in Fig. 3; and

Fig. 7 is a view similar to Fig. 3 showing a modified arrangement for connecting the inner end of the latch bar to the cover.

Referring to the accompanying drawing, our invention is shown in connection with a metallic receptacle 1 having an outstanding rim portion in the form of a circumferential bead 2 at the upper edge of its side wall. The receptacle or container 1 is also provided with the usual bail or handle 3 whose opposite ends are pivotally connected to ears or lugs 4 that are secured to the receptacle at diametrically opposite points. The opening at the upper end of the receptacle 1 is closed by means of a metal cover 5 having a depending circumferential flange or rim 6 adapted to fit over the beaded upper edge 2 of said receptacle.

The cover fastener comprises a latch bar, preferably in the form of a metal strap 7, that extends radially of the cover 5 from the outer edge thereof to a point located adjacent to the center thereof and is bowed or curved upwardly intermediate its ends to form a handle for said cover. The outer end portion of the latch bar 7 rests on the top of the cover 5 and terminates in a doubled-under hook portion 8 which extends downwardly over the rim 6 of said cover and thence inwardly through a slot 9 in said rim in position to slide beneath the bead 2 on the receptacle 1.

The inwardly extending portion of the hook 8 of the latch bar 7 is also provided at its end with oppositely projecting lugs 10 that extend beyond the ends of the slot 9 and thus prevent said hook from being disengaged from said slot. As shown in the drawing, a metal strap 11 is secured to the inner face of the depending rim 6 of the cover 5 at a point located diametrically opposite the slot 9, which receives the hook 8 of the latch bar 7, and is adapted to be positioned beneath the bead 2 of the receptacle 1 when said cover is initially placed thereon.

The downwardly extending inner end of the latch bar 7 is pivotally connected with one end of a link 12, whose other end is pivotally connected with the upwardly offset outer end portion of an anchor plate 13 that has its inner end portion riveted or otherwise rigidly secured flatwise to the bottom of a recess 14 provided therefor in the top of the cover 5. The inner end of the latch bar 7 is pivotally connected to the link 12, preferably by looping said end of said bar or strap through an elongated slot in the adjacent end of said link; and the upwardly offset outer end portion of the anchor plate 13 is secured to the other end of said link in a similar manner.

It is noted that in the open position of the fastener, the lugs 10 on the hook 8 at the outer end of the latch bar 7 will abut against the rim 6 of the cover 5 before the link 12 reaches an upright position, thereby preventing said link from swinging outwardly and downwardly when said latch bar is forced downwardly and thus sliding said bar

in a direction which would unlock the fastener. It is also noted that the length of the latch bar 7 is such that during its movement to locking position the hook 8 thereof binds on the edge of the cover 5 before the inner end of said latch bar reaches the horizontal plane in which the axis of the pivotal connection between the link 12 and anchor plate 13 is located, whereby pressure sufficient to spring the parts is necessary to swing said end of said latch bar below said plane with the result that upward swinging movement of the inner end of the latch bar is resisted and accidental unlocking of the fastener is prevented.

In the modification shown in Fig. 7, the inner end of the latch bar is connected to the cover by means of a hinge 15, one leaf of the hinge being secured flatwise to the top of the cover, and the other leaf being pivotally secured at its free end to the depending inner end portion of the latch bar.

With the arrangement described, the cover 5, after being placed on the receptacle 1 with the strap 11 on one side thereof located beneath the bead 2 of said receptacle, is locked to the receptacle by pressing the upwardly bowed handle portion of the latch bar 7 downwardly. This action causes the link 12 to swing inwardly and downwardly upon the anchor plate 13 and thus shift or slide the latch bar inwardly and cause the hooked outer end 8 thereof to slide beneath the bead 2 of the receptacle and lock the cover thereon. The fastening device is released by an upward pull on the inner end portion of the latch bar 7 which is slid outwardly by the upwardly and outwardly swinging movement of the supporting link 11 therefor far enough to move the inwardly extending end of the hook 8 clear of the bead 2 on the receptacle.

Obviously, the hereinbefore described arrangement admits of considerable modification, and we do not wish to be limited to the precise arrangement of parts shown and described.

What we claim is:

1. A receptacle having an outstanding rim portion, and a cover for said receptacle having a depending rim flange provided with an opening, and a cover fastener comprising a single latch bar mounted on said cover with its outer end projecting through the opening in the rim flange thereof beneath the rim portion of said receptacle, said latch bar having a downwardly bent inner end portion, and a link pivotally connected at one end to the downwardly bent inner end portion of said latch bar and to said cover at a point located intermediate between the ends of said latch bar and adapted by its swinging movement to shift said latch bar longitudinally to move the outer end thereof underneath or clear of the rim portion of said receptacle.
65. 2. A receptacle having an outstanding rim

portion, a cover for said receptacle having a depending rim flange provided on one side of said cover with a portion adapted to fit beneath the rim portion of said receptacle and on the opposite side of said cover with an opening and a cover fastener comprising a latch bar mounted on said cover and having a hooked outer end portion extending over the edge of said corner and through the opening in the rim flange thereof below the rim portion of the receptacle, an anchor plate secured to the top of said cover adjacent to the inner end of said latch bar, and a link connecting the inner end of said latch bar to said anchor plate, and adapted to shift the latch bar longitudinally to move the hooked outer end thereof beneath or clear of the rim portion of said receptacle, said hook portion of said latch bar being adapted to bind against the rim of said cover before the inner end of the latch bar reaches the level of the pivotal connection between the link and anchor plate, whereby pressure sufficient to spring the parts is necessary to swing the latch bar to locking position and the accidental unlocking of the fastener is prevented.

3. A receptacle having an outstanding rim portion, a cover for said receptacle having a depending rim flange provided on one side of said cover with a portion adapted to fit beneath the rim portion of said receptacle and on the opposite side of said cover with an opening and a cover fastener comprising a latch bar mounted on said cover and having a hooked outer end portion extending over the edge of said cover and through the opening in the rim flange thereof below the rim portion of the receptacle, and a link pivotally connected at one end to said cover and pivotally connected at its free end to the inner end of said latch bar and adapted to shift the latch bar longitudinally to move the hooked outer end thereof beneath or clear of the rim portion of said receptacle, said hook portion being provided with a projection adapted to abut against the inside face of the rim of said cover in the open position of said fastener to prevent outward and downward swinging movement of said link, said hook portion of said latch bar being adapted to bind against the rim of said cover before the inner end of the latch bar reaches the level of the pivotal connection between the link and said cover whereby pressure sufficient to spring the parts is necessary to swing the latch bar to locking position and the accidental unlocking of the fastener is prevented.

4. A receptacle having an outstanding rim portion, a cover for said receptacle, a latch bar mounted on said cover and having a downwardly and inwardly bent outer end portion extending over the edge of said cover and below the rim portion of said receptacle, said latch bar having a downwardly bent inner end portion, and a link pivotally connected at

one end to said cover and pivotally connected at its other end to the downwardly bent inner end portion of said latch bar, whereby the swinging movement of said link causes said latch bar to be shifted longitudinally to move the inwardly bent outer end portion thereof underneath or clear of the rim portion of said receptacle, said downwardly bent outer end portion of said latch bar being adapted to bind against the rim of said cover before the inner end of the latch bar reaches the level of the pivotal connection between said link and said pivot, whereby pressure sufficient to spring the parts is necessary to swing the latch bar to locking position.

15 Signed at St. Louis, Missouri, this 23 day of October, 1929.

MICHAEL SCHWARZ.
FRED J. GOETZ.
